FISHING LURE

Robert G. Spencer, 3922 Karen Manor Lane,
Memphis, Tenn.

Filed Apr. 14, 1972, Ser. No. 244,346

Term of patent 14 years

Int. Cl. D22—05

U.S. Cl. D22—27

FIG. 1

FIG. 2

FIG. 3

FIG. 4

FIG. 5

FIG. 6

FIG. 7

FIG. 8

FIG. 9

FIG. 10

FIG. 1 is a side view of a fishing lure, showing my new design.

FIG. 2 is a top view thereof.

FIG. 3 is a bottom view thereof.

FIG. 4 is a front view thereof.

FIG. 5 is a rear view thereof.

FIG. 6 is a side view of a fishing lure, showing a second embodiment of my invention.

FIG. 7 is a top view thereof.

FIG. 8 is a bottom view thereof.

FIG. 9 is a front view thereof.

FIG. 10 is a rear view thereof.

The side of my design opposite from the side shown in FIG. 1 has substantially the same appearance as that shown in FIG. 1.

The side of the second embodiment of my design opposite from the side shown in FIG. 6 has substantially the same appearance as that shown in FIG. 6.

I claim:

The ornamental design for a fishing lure, as shown and described.
